US00D938488S

(12) **United States Design Patent** (10) Patent No.: **US D938,488 S**
(45) Date of Patent: **** Dec. 14, 2021**

(54) **DISPLAY SCREEN OR PORTION THEREOF WITH GRAPHICAL USER INTERFACE**

(71) Applicant: **Lutron Technology Company LLC**,
Coopersburg, PA (US)

(72) Inventors: **Manisha Dahiya Baluja**, Lansdale, PA
(US); **John N. Callen**, Center Valley,
PA (US); **Erica L. Clymer**,
Northampton, PA (US); **Sanjeev
Kumar**, Harleysville, PA (US); **Mark
Law**, Bethlehem, PA (US); **Christopher
Spencer**, Coopersburg, PA (US)

(73) Assignee: **Lutron Technology Company LLC**,
Coopersburg, PA (US)

(**) Term: **15 Years**

(21) Appl. No.: **29/751,683**

(22) Filed: **Sep. 23, 2020**

Related U.S. Application Data

(63) Continuation of application No. 29/723,043, filed on Feb. 4, 2020, now Pat. No. Des. 900,159, which is a continuation of application No. 29/689,489, filed on Apr. 30, 2019, now Pat. No. Des. 877,774, which is a continuation of application No. 29/657,781, filed on Jul. 25, 2018, now Pat. No. Des. 848,476, which is a continuation of application No. 29/603,036, filed on May 5, 2017, now Pat. No. Des. 825,611, which is a continuation of application No. 29/553,804, filed on Feb. 4, 2016, now Pat. No. Des. 789,416.

CLAIM

The ornamental design for a display screen or portion thereof with graphical user interface, as shown and described.

DESCRIPTION

The file of this patent contains at least one drawing/photograph executed in color. Copies of this patent with color drawing(s)/photograph(s) will be provided by the Office upon request and payment of the necessary fee.

The sole FIGURE shows a display screen or portion thereof with graphical user interface showing our new design. The peripheral dashed broken lines illustrate a display screen or portion thereof, and form no part of the claimed design.
